THERAPEUTIC LAMP

Filed July 25, 1927

Patented Mar. 12, 1929.

1,705,300

UNITED STATES PATENT OFFICE.

ROLLAND H. MAXSON, OF MILTON, WISCONSIN, ASSIGNOR TO THE BURDICK CORPORATION, OF MILTON, WISCONSIN, A CORPORATION OF DELAWARE.

THERAPEUTIC LAMP.

Application filed July 25, 1927. Serial No. 208,170.

My invention relates to therapeutic lamps.

It will be explained as embodied in a relatively small portable lamp, such as is ordinarily used for more or less local treatments

5 in a physician's office, laboratory or at a patients' home, although, of course, it is applicable to larger sizes for more general application. The portable or smaller size, such as that chosen to illustrate the features 10 of the invention, may be more or less permanently mounted on any desired and appropriate support.

One of the objects of my invention is to provide an improved therapeutic lamp.

15 Another object is to provide an improved double-walled reflector for a therapeutic radiant energy generator.

Another object is to provide a well ventilated reflector.

20 Another object is to provide a relatively deep reflector with a comparatively flat reflecting surface.

Another object is to provide a lamp reflector-casing wherein the reflector can be 25 removed without disturbing any other part of the structure.

Another object is to provide a therapeutic lamp in which a ventilated casing is employed for surrounding the major part of 30 the reflector proper, the base portions of the radiant energy generating unit and electrical connecting members therefore so that during manipulation the operator will not touch the hot reflector walls nor disturb the supporting and electrical connections of the generating unit.

35 A further object is to provide a therapeutic lamp which is so constructed as to readily facilitate the removal of any element 40 thereof for replacement without the use of special tools.

45 A further object is to provide in a therapeutic lamp a reflector having a reinforcing offset portion at its periphery which also performs the additional function of serving as a positioning and holding element for an outer casing.

50 Another object is to provide a reflector of pleasing appearance, simple and rugged construction, and effective in use.

Other objects and advantages will herein-after appear.

55 An embodiment of the invention is illustrated in the accompanying drawing, where-

Fig. 1 is a side elevation, partly in section, of the assembled lamp, and

Fig. 2 is a sectional view on line 2-2 of Fig. 1.

The lamp comprises, in general, an outer 60 shell or casing A supporting an electrical screw plug receptacle B for receiving a radiant energy generating unit C, and a relatively flat dish shaped reflector D held within the casing A.

65 Casing A is substantially parabolic in contour and has a rearwardly extending somewhat cup shaped depressed portion 1 about its axis. This cup shaped extension has a flat rear wall 2 provided with a central 70 opening 4 through which the base of receptacle B projects.

75 The means for holding receptacle B fixed in the position shown in Fig. 1 includes four metal rods or bolts 5 having reduced portions 6 at their inner ends which extend through four equally spaced apart openings in a metal plate 7. Metal spacer sleeves 8 are disposed over portions 6 of rods 5 so as to space plate 7 a predetermined distance 80 from wall 2. Rods 5 are threaded at their rear ends and a pair of nuts 9 is disposed upon each of the threaded ends to securely anchor plate 7 thereto.

85 Receptacle B has a pair of outwardly projecting perforated lugs or ears 10 for receiving screws 11 which thread into holes in plate 7, and thus rigidly support base B with respect to casing A.

90 That portion 12 of base B which supports electrical terminals 13 and extends through opening 4 in wall 2, is covered by a cap 14. Cap 14 has skirt 15 through which the threaded and reduced ends of rods 5 project and which is clamped in place against nuts 9 by nuts 15 threaded upon the rear ends of the rods. Cap 14 has an annular lining 16 of fibre or similar insulating material to prevent contact between the terminal wires of conductor cord 17 and the walls of the metal 100 cap. A tubular threaded nipple 18 securely attached to cap 14 serves as a conduit through which the conductor cord is lead to the receptacle and as a support whereby the lamp may be attached to a suitable handle 105 or bracket.

110 Reflector D is of the shallow type so as to afford radiation of energy from unit C over a relatively large area at short range. The reflector is preferably constructed of light,

highly-polished metal, such as aluminum. Its outer end is flanged outwardly and then forwardly so as to provide an annular shoulder 20 against which the outer rim of the shell or casing can be tightly drawn and a substantially cylindrical shallow rim 21 projecting beyond the reflector. In order to strengthen the rim of the reflector, eliminate a sharp edge and improve its appearance, 10 the margin of the reflector is rolled outwardly into a bead 22. The rear of the reflector is provided with an axial opening through which the base of the generating element may be inserted into the receptacle. 15 This opening is surrounded by a rearwardly projecting flange 23 which may fit rather snugly about the base of the generating element. Around the margin of this opening in the reflector are a set of holes for receiving the outer ends of bolts 5 whose nuts 24 serve to draw and anchor the reflector and its outer shell together. Thus the rods or bolts 5 each cooperates with the reflector, receptacle, outer shell and rear cap to hold 25 the same together in a unit adapted to receive a radiant energy generating element.

In order that casing A may be kept relatively cool while in use, ventilating apertures 26 and 27 are provided through its side walls adjacent to and parallel with rim 3 and rearwardly extending portion 1, respectively.

The radiant energy generator may be of any appropriate type but I prefer to use and have illustrated the construction set forth in my co-pending application, Serial No. 193,221, filed May 21, 1917. In general, this element comprises an insulating base 30 carrying an outer screw plug shell 31 and center contact 32 for engaging the outer screw and inner contacts, respectively, of receptacle B. The base also carries a resistor 33 embedded in a rigid supporting and heat and light emitting envelope composed of 40 carbonium and a suitable binder. This resistor is connected to contacts 31 and 32 so that when the element is screwed into the reflector receptacle it is in circuit.

When the lamp is in service, it is supported on a handle by the operator or attached to some fixture or on a suitable standard. The reflector directs the rays of radiant energy and the outer shell or casing supports and protects the reflector, insures a good circulation of air thereabout, and shields the patient and operator from being burned if they should come in contact with it.

In the event that it becomes necessary to 60 replace the reflector D, it is only necessary to remove nuts 24 to release the reflector so that it may be readily removed and replaced.

The structure of the lamp is such that its outward appearance presents a substantially 65 uniform and unobstructed surface which

greatly enhances its appearance, the protruding rim of the reflector, because of its highly finished surfaces, greatly adding to the finished appearance thereof.

Having thus described my invention, what 70 I claim as new and desire to secure by Letters Patent of the United States is:

1. A therapeutic lamp comprising a casing open at the front, a concave reflector having a circumferential outwardly offset portion 75 at its periphery forming a shoulder on the outer wall of the reflector, disposed within said casing, said shoulder resting against the peripheral edge of the casing, means for mounting a radiant energy generating unit 80 in said lamp with the active portion thereof in front of said reflector, and means for securing said reflector against movement with respect to said casing.

2. A therapeutic lamp reflector casing 85 comprising a parabolic-like outer shell, a relatively flat reflector within the shell and having an annular flange to provide a shoulder against which the edge of the shell is drawn and a rim projecting beyond the 90 shoulder, a receptacle within the rear part of the shell, and means for clamping the shell, reflector and receptacle together.

3. A therapeutic lamp reflector casing comprising a flaring dish shaped reflector 95 having an opening through its smaller end and an annular shoulder adjacent its larger end, a flaring outer shell within which the reflector is mounted, a receptacle for holding a radiant energy generating element, a plate 100 attached to the receptacle, and a series of bolts each of which passes through the reflector, shell and plate to anchor the parts together and draw the outer shell against the shoulder of the reflector.

4. A therapeutic lamp reflector casing comprising a flaring outer shell having an opening through its smaller rear end, a reflector within the outer shell, a cup covering the opening in the rear end of the shell, a 110 receptacle located in the rear of the shell to receive a radiant energy generating element inserted through the opening in the reflector for securing the receptacle in position within the shell, and means for securing the reflector and the cup against movement with respect to the shell.

5. A therapeutic lamp comprising a shallow reflector, a relatively deep casing partially receiving the reflector, a radiant energy generating unit, means including a plate, for mounting said generating unit free from contact with said deep casing with its inactive portions in said deep casing and its active portion in front of said reflector 120 and other means associated with said first-named means for securing the reflector against movement with respect to the casing and for supporting said plate.

6. A therapeutic lamp reflector casing 130

comprising a flaring dish-shaped reflector having an opening through its smaller end, a flaring outer shell within which the reflector is mounted, a receptacle for holding a 5 radiant energy generating element, a plate attached to the receptacle, a plurality of bolts, each of which pass through the inner end of the flaring outer shell through said

plate and through the inner end of the dish-shaped reflector adjacent to the opening at 10 its smaller end to draw the parts together and to support the plate with its receptacle free from contact with the reflector and shell.

In witness whereof, I hereunto subscribe my name this 18th day of July, 1927.

ROLLAND H. MAXSON.
